UNITED STATES PATENT OFFICE.

GOTTFRIED HUOVINEN, OF PALISADES PARK, NEW JERSEY.

BUILDING CONSTRUCTION AND BLOCK.

Application filed December 28, 1926. Serial No. 157,549.

The present invention is concerned with the provision of a new type of building block capable of a wide range of utility, but peculiarly suited for the construction of small buildings which are adapted to withstand heavy wind storms or the like.

One object of the invention is to provide a building construction in which the walls formed of my improved concrete blocks are anchored to the footings, and the roof anchored to the walls, so that there will be no danger of the roof being torn away by wind pressure.

A further object of the invention is to provide a building block so constructed that moisture cannot penetrate to the interior of the building through the mortar which connects the blocks, and being so arranged that not only subjacent and superjacent tiers of blocks may be locked together by reinforcements, but adjacent blocks of each individual tier may be interlocked by reinforcements.

Other and more general objects of the invention are to provide a building block of simple practical construction which will be rugged, durable and efficient in use, and with which a peculiarly strong, durable and inexpensive building may be rapidly erected.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a fragmentary broken vertical sectional view through one wall and a portion of the roof of a building constructed in accordance with the present invention.

Fig. 2 is a perspective view of one of the blocks, the dotted lines indicating the line of division to be followed when forming half blocks.

Fig. 3 is a sectional plan view showing the corner of the building in course of erection.

Fig. 4 is an edge view of one of the anchoring straps for the roof rafters.

The particular type of building block shown in Fig. 2 is formed of concrete or other suitable material, and is of general rectangular shape in longitudinal section, the block being preferably, although not necessarily of square cross sectional

shape in transverse section, as it customary in the art.

The block is designated at 10, and extending transversely therethrough are four relatively large openings 11 which define air spaces within the block. These openings also cooperatively define a longitudinally extending interior partition 12 and a transversely interior partition 13 which intersects the longitudinal partition. At diagonally opposite corners of the block, the block walls are slightly thickened to provide for cylindrical holes 14 extending transversely through the block and adapted to receive reinforcing rods. The transverse partition 13 is also slightly thickened at opposite sides of opposite ends to provide ample material around similar cylindrical openings 15, the openings 14 and 15 of each side of the block being separated by a distance of approximately one half block, and being spaced on opposite sides of the central partition 13.

This arrangement of openings 15 permits the opening of superjacent and subjacent tiers of blocks to be accurately aligned either when the blocks are directly piled one upon the other, or when the blocks are arranged in staggered relationship with one block overlying the ends of two adjacent blocks. It also, as seen in Fig. 3, permits registration of two of the openings of one block with two openings of a superjacent or subjacent block laid at right angles thereto, as at the corner of a building.

Referring now to Figs. 1 and 3 of the drawings, I have illustrated a preferred manner of use of the blocks. The building which I have shown includes a substantial concrete footing 16 in which are embedded the intermediate portions of U-shaped reinforcing members 17, the free hooked ends of which project upwardly and are adapted to enter certain of the openings 14 or 15 in the first tier of blocks 10 which are laid upon the footing. The construction is such that the hooked ends of the reinforcements may either enter two of the openings 14, 15 of one block, or may enter the openings 14 or 15 of laterally adjacent blocks, locking the blocks together.

After the first tier of blocks has been laid, a second tier is superimposed on the lower tier, the latter tier being staggered relatively to the former one, and having its openings 14, 15 aligning with similar open-

ings in the lower tier. Reinforcing rods 18 are now inserted through the openings in the second tier of blocks, their ends engaged with the hooked upper ends of the reinforcing members 17, and the rods 18 pulled forcibly upwardly to firmly interengage them with the reinforcements 17. Concrete 17^a is now poured into the aligned openings 14, 15 of the two emplaced tiers and tamped down, leaving the projecting upper ends of the rods 18 exposed. Two more tiers of blocks are applied and new sets of reinforcing rods inserted and anchored by pouring more concrete. The uppermost reinforcing rods of the series are designated at 19 and are provided with offset upper ends 20 hooked as at 21 to engage a roof rafter 22. The strap-like offset portions 20 of the upper tie rods are preferably bolted as at 23 to the rafter, and the rafter may be cut away as at 24 to freely receive the hooked portions 21.

By virtue of this construction, the blocks of the walls are anchored and tied to the footing, and the roof rafters are anchored and tied to the walls, so that the building will be substantially proof against damage by wind storms.

Preferably, at least one end of each block is formed with grooves 25, these grooves defining with the flat wall of an adjacent block, air pockets, so that when the mortar is applied between the two blocks, there will be air spaces or interruptions in at least two places at the joint so that moisture cannot penetrate to the interior of the building through the mortar.

Obviously, various changes and alterations might be made in the general form and arrangement of the parts described without departing from the invention. Hence I do

not wish to limit myself to the details set forth, but shall consider myself at liberty to make such changes and alterations as fairly fall within the spirit and scope of the appended claims.

I claim:

1. In a building construction, a footing, a wall of superimposed concrete blocks anchored to the footing and a series of roof rafters tied to the footing through the blocks, the means for tying the footing and rafters together comprising reinforcing bars passing through the blocks and anchored at their ends to the footing and rafters respectively.

2. In a building construction, a footing, a wall of superimposed concrete blocks anchored to the footing and a series of roof rafters tied to the footing through the blocks, reinforcing members embedded in the footing and extending upwardly into aligned openings in the blocks, a vertical series of reinforcing bars having hooked engagement with each other and with the footing, reinforcements, and rafter engaging hooks having hooked engagement with the uppermost of the series of reinforcing bars.

3. A building as set forth in claim 2, wherein the block openings are filled with concrete to embed the reinforcing bars.

4. In a building construction, a footing, a wall of superimposed concrete blocks anchored to the footing and a series of roof rafters tied to the footing through the blocks, the blocks being arranged in tiers tied together, the blocks of adjacent tiers being staggered and the blocks of each tier being tied to adjacent blocks of said tier.

GOTTFRIED HUOVINEN.
